UNITED STATES PATENT OFFICE.

CLIFFORD N. McCALLUM, OF SEATTLE, WASHINGTON, ASSIGNOR TO SKINNER AND EDDY SHIPBUILDING CO., OF SEATTLE, WASHINGTON.

PNEUMATIC FRAME BENDER.

1,410,691.

Specification of Letters Patent. Patented Mar. 28, 1922.

Application filed April 13, 1920. Serial No. 373,483.

To all whom it may concern:

Be it known that I, CLIFFORD N. McCALLUM, a citizen of the United States, residing at Seattle, in the county of King and State 5 of Washington, have invented a certain new and useful Pneumatic Frame Bender, of which the following is a specification.

My invention relates to a "pneumatic frame bender". More particularly the device embodying my invention is designed 10 to bend the steel members forming the hull frame of steel ships, being operated in association with a perforated platform, called the "slabs".

15 In constructing the frame of a steel ship's hull, practically all the members require some bending necessitated both by the varying shape of a ship hull cross sectionally considered and the usual flaring and tumble 20 home lines of the ship hull. For example, the beams which constitute the side ribs and the various angle irons must all be curved to adapt them to their special position in the hull. Each of these rib members with its 25 corresponding member on the opposite side of the hull must be given a bend having a degree of curvature differing from all the others depending upon its position, that is, its distance from the bow. Not only must 30 these all be different in the same hull, but they must vary in hulls of different sizes or capacities. Hence, it is manifest that it is of great practical advantage to have a device that can be used in giving this wide 35 range of curvatures to the various steel members differing greatly in size from one another which go to make up the frame work of a ship hull. In short, no standard mould will meet the situation which on the 40 contrary demands a device which is characterized by its universal adaptability.

45 For such bending, the steel members must be heated and hence the device designed to bend these members must be adapted to be applied to them in a heated condition. Moreover such device must be capable of exerting and sustaining a great force owing to the magnitude of some of the frame members and this force must be instantly controllable so that its application can be stopped promptly when the desired degree 50 of curvature is reached and the frame member being treated is properly secured in position while cooling. Further, this force must be exerted in a plane low down, paral-

leling and adjacent to the plane of the platform floor or slabs, i. e. on the plane of support of the beam which is to be bent. This may be called the "working plane" of the device. The beam being in a highly heated 60 condition would be greatly distorted if such force was applied otherwise than on the line of support of the weight of the beam. Thus, is presented the difficulty of providing a device of sufficient power and at the same time 65 not have a piston of large diameter, which obviously would introduce an objectionably large step down to reach the "working plane".

Moreover, such device must be light of 70 weight and capable of being quickly and easily moved about—otherwise the member being shaped will have cooled to a point where it cannot be properly bent, and a re-heating would be necessary which may be 75 impossible if the degree of curvature is great, because the furnace might not be of sufficient width to receive such member in a bent condition. On the other hand while the device must be capable of being quickly 80 moved about yet it must provide for automatically anchoring itself when positioned so that it can exert its force and also it must provide for automatically unanchoring it- 85 self when it is to be repositioned.

Furthermore, parts of such device are sub- 90 ject to great wear and must be readily replaceable. Such is the situation with respect to the part herein designated as a ram. Finally, such a machine must be simple in construction so that it can be repaired by 95 operators, who are not machinists.

In general, the objects of my invention are to provide a frame bending device which will satisfy all these conditions. More par- 95 ticularly the objects of my invention are to provide a frame bending device; which will have a wide range of adaptability so that it will bend the various frame members of steel ship hulls giving to each member its 100 particular degree of curvature; which will be capable of exerting a great force on a low working plane, i. e. on the plane of the support of the beam to be bent; which will be capable of being easily and quickly 105 moved about and at the same time capable of automatically anchoring itself when positioned and of automatically unanchoring itself when repositioned, and which will be characterized by its portability, simplicity, 110

ability to maintain or sustain a great force, and the facility with which worn parts may be replaced.

The above mentioned general objects of 5 my invention together with others inherent in the same are attained by the mechanism illustrated in the following drawings, the same being merely a preferred exemplary form of embodiment of my invention, 10 throughout which drawings like reference numerals indicate like parts:

Figure 1 is a partial sectional view of a device embodying my invention showing one cylinder from above and one cylinder in 15 longitudinal section;

Figure 2 is a vertical sectional view of the same on broken line 2, 2 of Fig. 1;

Fig. 3 is a cross sectional view on broken 20 line 3, 3 of Fig. 1; and

Fig. 4 is a view showing the application of the same to the bending of a frame member.

In two cylinders 5 and 6 are disposed pistons 7 which are respectively provided with rods 8 and 9. To the ends of these rods 8 25 and 9, a crosshead member 10 is secured. To the underside of this is bolted by bolts 11 the ram 12 which member extends nearly the length of the machine. On the forward end of the ram 12 is the toe 13 which drops below 30 the plane of the underside of the ram. The removable plate 14 holds the ram 12 in its channel 15, said plate being held in position by bolts 16. On the rear end of the device and centering on the longitudinal axis is the 35 anchoring pin 17 extending for a short distance below the longitudinal plane of its holding casting 18.

Compressed air or fluid conduits 19 and 40 20 have a conventional four way valve 21 in common, and a flexible conduit 22 affords a means to connect the device with the main air or fluid line, said conduit attaching on the side of the four way valve 21. Conduit 19 leads to the rear cross-conduit 23 in the 45 walls of the device. This cross-conduit 23 opens through ports 24 and 25 into the cylinders 5 and 6 in their rear end portion. Conduit 20 leads to the front cross conduit 26 in the walls of the device, said conduit 26 50 opening through ports 27 and 28 into the front end portions of the cylinders 5 and 6. The four way valve 21 has an outlet port 29 through which the air in the cylinders exhausts. Pet cocks 30 and 31 are provided for 55 each of the cylinders 5 and 6 for drain purposes.

The valve 21 is provided with a stem extension handle 32. A handle 33 having yoke arms 34 serves in moving the device about. 60 Wheels 35 are secured to the end of the arms 34 which arms are pivotally secured at 36 and 37 to the device a short distance above the ends of said yoke arms,—said pivot points being back of the center of gravity 65 of the device.

In general, the application and operation of my device is as follows: On an iron platform 38 provided with perforations 39, said platform being commonly referred to or known as the slabs, a curved line 40 is chalked according to the pattern frame prepared for the particular member to be shaped and pins 41 are made fast in such of the perforations 39 as are intercepted by this line. The beam 42 to be bent is drawn out 75 of a furnace adjoining said platform and one end is made fast by pins 43 driven into the holes 39 in which they are caused to bind. Then the device herein described is positioned and anchored by pin 17 successively 80 at points along said beam 42 and the ram 12 is caused to bear against the said beam and push it till its edges bear against the pins 41 at that point, whereupon the beam is made fast by the pins 44,—all of said pins 85 being of similar construction and having a slight bend in their shank to cause them to bind in the holes 39. Then, the machine is moved to another point along the beam and the operation repeated.

More particularly, the operation of my invention is as follows: Compressed air or fluid is supplied to the device by means of the flexible conduit 22, which may be conveniently yieldingly suspended over head 90 by a weight balanced over a pulley whereby said flexible air conduit is kept out of the way of the operators on the slabs. The handle 33 is elevated so as to lower the wheels 35 below the plane of the plate 14 100 and so raise the rear end of the device sufficiently so that the anchoring pin 17 clears the surface of the slabs. Let it be particularly noted that the center of gravity of the device is forward of the pivot points 36 and 105 37 so that upon raising the handle 33, the anchoring pin 17 is certain to be automatically withdrawn from one of the perforations 39 because only the rear end is elevated when the handle is raised. However, 110 only enough weight is forward to make sure that the front end will not raise and to permit the front end to bear lightly upon the slabs, i. e. so that most all the weight is carried by the wheels, only enough being 115 thrown forward to insure the rear end alone rising when the handle is elevated. The device is then dragged to the point of the beam against which it is to bear whereupon the handle is lowered in order to raise the wheels 120 35 and let the anchoring pin 17 automatically extend into one of the perforations 39. Then the valve extension handle 32 is turned to permit the air pressure to extend through conduits 19 and 23 and ports 24 and 25 and 125 strike upon the pistons 7 of each cylinder 5 and 6 with equal force. These pistons are thus forced forward and push outwardly the rods 8 and 9. This outward push is combined by means of the crosshead 10 and 130

made to actuate the ram 12. At first, the pressure is turned on partially to cause the ram to extend slowly until its toe 13 comes into actual contact with the beam 42,—thus 5 is avoided a sudden blow which might damage the device. The air in front of the pistons 7 exhausts through conduits 20 and 26, valve 21 and outlet 29. Thereafter, the pressure is increased as required until the beam is 10 forced back to the line of pins (41) secured on the line of the chalk mark 40. When the beam has been securely pinned down as above explained by pins 44 the valve 21 is turned by means of the stem extension 15 handle 32 so that the air pressure is caused to extend through conduits 20 and 26 and ports 27 and 28 whereby the pistons 7 are forced backwardly,—the air in the rear of the pistons exhausting through the conduits 20 19, valve 21 and the outlet 29. The forcing back of the pistons 7 retracts the ram 12.

The ram 12 has a long bearing on the walls of its channel 15 throughout the length of its stroke and in this wise objectionable 25 side thrusts or pressure is removed from the piston rods 8 and 9. The ram 12 from the great pressures to which it is subjected in time becomes distorted and must be replaced. For this purpose, the plate 14 is 30 provided and is readily removed by taking out the bolts 16 and the bolts 11 of the cross-head member 10.

It is to be particularly noted that the working plane of the ram 12 is practically 35 the line 45 of support of the beam 42, i. e. in the plane paralleling and adjacent to the plane of the platform or slabs 38. The ram 12 must be actuated with great force. To develop the requisite amount of power in 40 one cylinder would require a piston of great diameter and hence an impractically large step down in the toe 13 would be necessary to enable the ram to operate on the said low working plane. To keep the axis of the pistons 45 on a sufficiently low plane and yet provide the requisite power, two pistons of small diameter are provided and the force of the two combined by means of the cross-

head member (10), to the underside of which the ram 12 is secured. 50

Obviously, changes may be made in the forms, dimensions, and arrangement of the parts of my invention, without departing from the principle thereof, the above setting forth only a preferred form of embodiment. 55

I claim—

1. A pneumatic frame bender embodying two cylinders positioned side by side, pistons disposed in said cylinders, piston rods carried by said pistons, a crosshead joining said rods, a ram carried by said crosshead, said ram extending nearly the entire length of the device, a removable plate disposed to hold said ram in place, an anchoring pin, compressed air conduits leading to the front 60 and rear end portions of said cylinders, a fourway valve whereby compressed air may be caused to flow alternately to the front and rear ends of said cylinders to actuate said pistons. 70

2. A pneumatic frame bender embodying two cylinders of relatively small diameter positioned side by side, pistons disposed in said cylinders, piston rods carried by said pistons, a crosshead joining said rods, a 75 ram carried by said crosshead, said ram extending nearly the entire length of the device and having a toe disposed on one end whereby and by means of said relatively small diameter cylinders a low working 80 plane is provided, a removable plate disposed to hold said ram in place, an anchoring pin, a handle with yoke arms, wheels operatively disposed on the end portion of said arms which arms are pivotally secured to the de- 85 vice at such a point as to throw the center of gravity forwardly of said pivot point, compressed air conduits leading to the front and rear end portions of said cylinders, and a four way valve whereby compressed air may 90 be caused to flow alternately to the front and rear ends of said cylinders to actuate said pistons.

In witness whereof, I hereunto subscribe my name this 2nd day of April, A. D. 1920. 95

CLIFFORD N. McCALLUM.
